TRIPLE VALVE.

1,302,984.

Specification of Letters Patent.

Patented May 6, 1919.

Application filed June 10, 1914, Serial No. 844,275. Renewed February 17, 1919. Serial No. 277,651.

To all whom it may concern:

Be it known that I, JACOB RUSH SNYDER, a resident of Pittsburgh, in the county of Allegheny and State of Pennsylvania, have 5 invented a new and useful Improvement in Triple Valves, of which the following is a specification.

This invention relates to triple and control valves for air brake systems.

10 The object of the invention is to provide means in conjunction with triple and control valves whereby upon service reductions in train pipe pressure the valve is prevented from accidentally going to quick action or 15 emergency position.

With present forms of quick action triple and control valves for freight and passenger cars and locomotive service, it frequently happens that the main piston fails to move 20 to service application position upon initial service reductions of train pipe pressure. This is due to a variety of causes, such as insufficient or imperfect lubrication, improperly fitted packing rings, binding of packing rings and pistons, dirt in the valve, and numerous other causes. As a result of the 25 failure of the triple valve to move upon initial reduction of train pipe pressure, substantially the full auxiliary reservoir pressure 30 is retained on the auxiliary side of the main piston. Consequently, when the valve moves under the second or third reduction of train pipe pressure, this excess pressure on the auxiliary reservoir side moves the piston 35 over so violently that the standard graduating spring does not stop the valve in service position, as a consequence of which an undesired quick action or emergency application is brought about. This invariably 40 means the pulling out of draw bars or some other serious injury to the train.

The object of the present invention is to provide a triple or control valve of the type where train pipe pressure is vented to the brake cylinder in quick actions, with 45 means whereby the undesired quick action on service reductions of train pipe pressure cannot occur, no matter how much the triple valve piston may stick.

50 The invention comprises the construction and arrangement of parts hereinafter described and claimed.

In the accompanying drawings Figure 1 is a longitudinal section through a portion of

a triple valve with the improvements applied thereto showing the same in normal or running position, and Fig. 2 is a longitudinal vertical section through the same parts, but taken on a different plane from that of Fig. 1, and also showing the parts 55 in normal or running position.

The improvements of this application are applicable to that type of triple valve in which the main piston in emergency position unseats a valve for admitting pressure from 60 the train pipe to the brake cylinder, and more particularly a triple valve in which the emergency valve is actuated by the graduating stem, such as shown in my applications Serial No. 727,542, filed Oct. 24, 70 1912 and Serial No. 818,571, filed Feb. 13, 1914.

Only a portion of the triple valve is shown, as it is not important just how the ports in the main valve seat are arranged. In the 75 drawings, 1 indicates a portion of the main casing in which is the usual bushing 2 enclosing a chamber 3 which is open to the train pipe through the train pipe passage 4 and in which chamber 3 works the main piston 5. This piston operates slide valves of 80 any preferred type and under variations of train pipe pressure effects the usual functions of applying and releasing the brakes.

In the head 6 is slidably mounted the 85 graduating stem 7, which is acted against by the graduating spring 8, and which serves in the outward movement of the main piston 5 under gradual or service reductions of train pipe pressure to arrest said piston 90 5 in service application position, as will be understood. Surrounding the graduating stem 7 is a bushing 10 in which is a cavity 11 communicating with the passage 12 leading to the brake cylinder. The outer end 95 of the bushing 10 forms a seat for a valve 14 which surrounds the graduating stem 7 and is slidable on said stem. This valve is provided with a sleeve 15 and the stem is provided with a collar 16, which sleeve and 100 collar are so located with reference to each other that the stem is free to move outwardly under service reductions without contacting with sleeve 15, but upon emergency reductions of train pipe pressure the full outward 105 travel of the main piston moves the graduating stem 7 outwardly so far that collar 16 engages sleeve 15 and unseats the valve 14.

The chamber 17 in the outer portion of the head 6 is open to train pipe pressure through port 18 and passage 19 so that the unseating of the valve 14 permits train pipe pressure to flow through the cavity 11 and passage 12 to the brake cylinder, thereby securing the local venting of the train pipe necessary for quick or emergency action. The valve so far described may be in all particulars the same as that described and illustrated in my applications above referred to, but the main slide valves (not herein illustrated) may be of any other suitable type.

In order to prevent the undesired quick action of the triple valve in case the piston should stick during the initial service reductions of train pipe pressure and move outwardly with great force under a later reduction of service train pipe pressure, the following arrangement is provided. The valve 14 is carried by a piston 21, which works in the chamber 17 and whose outer face is constantly open to the train pipe pressure in said chamber 17, while its inner face is in part normally open to atmospheric pressure in the cavity 11 (due to the brake cylinders being released) and in part to a pressure equal to train pipe pressure, to-wit, in the annular chamber 22 which is connected to chamber 17 by means of a suitable equalizing passage, shown as an opening 23 through the piston 21 and is controlled by a check valve 24 opening toward the annular chamber 22 and normally held to its seat by a light spring 25. An additional equalizing passage is also provided between chambers 17 and 22, and is shown as a small port 26 through the check valve 24, but may be a port or passage located at any other position. The opening 23 through the piston 21 is of larger area than the port 18 connecting chamber 17 with the train pipe passage 19. The piston 21 also controls a port 27 leading to the train pipe passage 19.

Normally the piston 21 is in position to seat the valve 14 against the inner end of bushing 10, and when the brakes are released the piston 21 is differential, being subject for its entire outer area to train pipe pressure in chamber 17, while on its inner face it is subject to a similar pressure for only that portion of its area represented by the annular space 22, the central portion of the piston being subject to atmospheric pressure. The piston is furthermore held against the seat on bushing 10 by a graduating spring 8 acting through the graduating stem and holding collar 16 against the outer face of the piston. In normal or running position the pressures in chambers 17 and 22 are equal to each other and to the train pipe pressure.

Upon service reductions of train pipe pressure the piston 5 moves outwardly, and such outward movement ordinarily is ar-

rested by the graduating spring 8, which ordinarily brings the piston to rest in service position before the collar 16 contacts with the sleeve 15. Should, however, the piston stick during initial service reductions of train pipe pressure, and move under a subsequent service reduction of train pipe pressure (and with a greater force), it will nevertheless be arrested as soon as the collar 16 contacts with the sleeve 15, being then resisted not only by the greater resistance of spring 8 (which has become considerably compressed), but also by the differential piston 21, the differential of which will be made sufficient to overcome any excess pressure likely to occur on the auxiliary reservoir side of the main piston. Consequently, the device shown will to a large extent prevent the undesired quick action of the triple valve, as above described. A service reduction of pressure necessarily reduces the pressure in chamber 17, but the pressure in chamber 22 will always equalize therewith through the equalizing port 26, which is large enough to permit such equalization as rapidly as required in service reductions. This equalization takes place each time the train pipe pressure is reduced for service application, and entirely irrespective of whether the main piston has moved or not. Consequently, the piston 21 is always a differential one in service reductions.

When however, the train pipe pressure is suddenly reduced, such as by an emergency application, or by a burst hose, the reduction in chamber 17 is so rapid that the small port 26 is not sufficient to equalize chamber 22 with chamber 17. Consequently, the differential value of the piston 21 is destroyed, so that the sudden outward movement of the main piston 5 will, when the collar 16 contacts with the sleeve 15, move the piston 21 outwardly, thereby unseating valve 14. This permits the pressure in chamber 22 to at once escape to the brake cylinder, thereby almost instantly entirely reducing the pressure on the inner face of piston 21. In order to prevent the valve 14 from again immediately seating under the pressure in chamber 17, the check valve 24 is provided, which is merely held to its seat by the light spring 25, so that as soon as the pressure in chamber 22 is reduced, this check valve opens and admits air in a relatively large volume to chamber 22. The passage controlled by the check valve 24 is larger than the port 18 connecting chamber 17 with the train pipe and consequently the pressure from chamber 17 will equalize into chamber 22 and prevent the piston from again seating valve 24, and, indeed, the piston will continue to move outwardly until it uncovers the port 27 whereupon train pipe pressure flows directly to cavity 11 and thence to the brake cylinder thus providing

for the necessary local venting of the train pipe to secure the quick action of the brakes throughout the train.

The invention described is applicable to any form of triple valve in which the outward movement of the main piston unseats the emergency valve, and the actuation of the supplementary devices is dependent upon the differential effect of the supplementary piston, which differential effect must be sufficiently great to assist the graduating spring in preventing the main piston from moving outwardly sufficiently to unseat the train pipe vent valve under any such differential pressure as the main piston may be subject to in service reductions of train pipe pressure when the main valve sticks.

What I claim is:—

1. In a triple or control valve mechanism, the combination of a main movable abutment actuated by variations of train pipe pressure and effecting the usual combinations between the train pipe and auxiliary reservoir, auxiliary reservoir and brake cylinder, and brake cylinder and atmosphere, and a supplementary abutment subject on one side to train pipe pressure, on a portion of its opposite side to an equal trapped pressure and on a portion of said side to a lesser pressure, said supplementary abutment controlling a train pipe vent valve, and a check valve controlling a communication between the two faces of said supplementary abutment and seating toward the train pipe side thereof.

2. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a train pipe vent valve arranged to be opened by the movement of the main piston under emergency reductions of train pipe pressure, a supplementary movable abutment acting against such train pipe vent valve and subject on one face to train pipe pressure, on a portion of its opposite face to an equal trapped pressure, and on a portion of said side to a lesser pressure, and a restricted equalizing port connecting the faces of said vent valve.

3. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a train pipe vent valve arranged to be opened upon movement of the movable abutment under emergency reductions of train pipe pressure, a supplementary movable abutment acting

against said emergency valve and open on one face to train pipe pressure and on a portion of its opposite face to an equal trapped pressure, a check valve controlling communication between the two faces of said movable abutment and seating toward the train pipe side thereof, and a restricted equalizing passage between the two faces of said movable abutment.

4. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a supplementary abutment subject on its opposite faces to varying pressures and a check valve controlling communication between the two faces of said supplementary abutment and seating toward the train pipe side thereof.

5. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, and a supplementary abutment subject on one side to train pipe pressure and on a portion of its opposite side to an equal trapped pressure, said supplementary abutment controlling a train pipe vent valve, and a check valve controlling a communication between the two faces of said supplementary abutment and seating toward the train pipe side thereof.

6. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a graduating stem and a graduating spring arranged to control the movement of said movable abutment, a train pipe vent valve slideable on said graduating stem and arranged to be opened by the movement of said graduating stem outwardly under emergency application movements of the movable abutment, and a differential piston mechanism operable only upon emergency reductions of train pipe pressure and arranged to prevent the unseating of said vent valve under service reductions of train pipe pressure.

7. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a graduating stem and a graduating spring ar-

ranged to control the movement of said movable abutment, a train pipe vent valve slideable on said graduating stem and arranged to be opened by the movement of said graduating stem outwardly under emergency application movements of the movable abutment, a supplementary movable abutment acting on said vent valve and subject on its outer face to train pipe pressure and on a portion of its inner face to an equal trapped pressure, and an equalizing connection between the two faces of said abutment arranged to permit equalization under service reductions of train pipe pressure but prevent equalization upon emergency reductions of train pipe pressure.

8. In a triple or control valve mechanism, the combination of the main movable abutment actuated by variations of train pipe pressure and effecting the usual combinations between the train pipe and auxiliary reservoir, auxiliary reservoir and brake cylinder, and brake cylinder and atmosphere, a graduating stem and a graduating spring arranged to control the movement of said

movable abutment, a train pipe vent valve slideable on said graduating stem and arranged to be opened by the movement of said graduating stem outwardly under emergency application movements of the movable abutment, a supplementary movable abutment acting on said vent valve and subject on its outer face to train pipe pressure and on a portion of its inner face to an equal trapped pressure, an equalizing connection between the two faces of said abutment arranged to permit equalization upon service reductions of train pipe pressure but prevent equalization upon emergency reductions of train pipe pressure, and a passage between the two faces of said movable abutment controlled by a check valve seating toward the train pipe side thereof.

In testimony whereof I have hereunto set my hand.

JACOB RUSH SNYDER.
